UNITED STATES PATENT OFFICE.

EDGAR W. MYERS, OF LOS ANGELES, CALIFORNIA, ASSIGNOR TO FILMUSIC COMPANY,
A CORPORATION OF CALIFORNIA.

MACHINE FOR MAKING MUSIC-ROLLS.

1,366,017.

Specification of Letters Patent.

Patented Jan. 18, 1921.

Application filed May 20, 1918. Serial No. 235,704.

To all whom it may concern:

Be it known that I, EDGAR W. MYERS, a citizen of the United States, and resident of Los Angeles, in the State of California, have invented a certain new and useful Improvement in Machines for Making Music-Rolls, and do hereby declare that the following is a full, clear, and exact description thereof.

10 My invention relates to machines for perforating sheet material, and in particular to machines for making master sheets for the reproduction of perforated sheet music for piano playing and like machines, and generally stated my object is to provide a machine for this purpose of high efficiency and accuracy in the production of the perforations corresponding to the notes to be rendered, and which, while capable of accurate 15 or close adjustment, will be simple, not apt to get out of order and lasting, and for the attainment of my object and others, which will be evident to those skilled in the art when the structure embodying my invention 20 is understood, my said invention consists in the mechanism constructed substantially as hereinafter specified and claimed.

In the accompanying drawings—

Figure 1 is a side elevation of a machine 30 embodying my invention with parts in vertical section;

Fig. 2 is a detail top plan view.

As a brief preliminary description of the machine shown in the drawings for illustrating an embodiment of my invention, such machine comprehends a gang or row of side by side punches, a constantly reciprocating device for each punch and means for selectively placing the punches in operative 35 connection with the reciprocating devices according to the notes to be mechanically reproduced on the player instrument, such notes and the time value thereof being those rendered initially on the piano, or other instrument, the blank paper to form the master sheet being, of course, fed past the row or gang of punches. The speed of reciprocation of the punches, as is common in this art, is such that an opening, or slot of a 40 length corresponding to the time value of the note, will result from the rapid reciprocation of the punches, a succession of reciprocations resulting in a continuous slot.

Taking up now the detailed description 55 of the machine shown in the drawings, it

will be found to comprise a frame conveniently made of cast iron having two end plates 10. Journaled in bearings in said end plates is a main driving shaft 11 having on one end, beyond one of the end plates, a pulley 12 which is a convenient means of applying power to said shaft to revolve it. Adjacent to the outer side of each end plate 10, the driving shaft has an eccentric 13 upon which is placed a pitman, 60 or link 14 that extends horizontally and is pivotally connected to a horizontal bolt or shaft 15, hung or suspended by a link 16 at each end, from the side frames 10, said shaft 15 being thus free to oscillate horizontally by the action of the eccentrics on the pitman. Pivotedly mounted on the shaft 15 is a series of levers or fingers 17, each of which, at one end, is connected by a wire 18 to the piano-key action, and at 65 its opposite end has a vertical notch 19 in its upper side that provides two spaced shoulders, the forward one of which is higher than the other, and by the upward movement of the notch, it is moved over the 70 downturned end or projection 20 of a punch 21 that is slidable horizontally in a guide hole 22 in a cross bar 23 secured, as by screws, to the frame plates, and when the notch passes over the punch end, the punch 75 partakes of the horizontal reciprocations of the lever or finger 17, being engaged first by one notch shoulder and then by the other shoulder. As soon as the piano key is released, the finger connected therewith 80 drops, and, preferably, it is acted on by a spring device 24 to assure its dropping to carry that one of the notch shoulders which moves the punch forward, low enough to clear the punch projection so that, until 85 that particular piano key is again depressed, the finger 17 will reciprocate idly. However, the notch shoulder that serves to retract the punch, is prevented dropping far enough to clear the punch projection and 90 thereby it is made certain that the punch will always be retracted. It is so prevented by a ledge 25 that projects from the punch guide bar below the end of the finger 17. The spring device 24 shown, is in the form 95 of a spring pressed plunger mounted in a socket in a cross bar 26 above the series of fingers 17.

Alining with each punch is a die hole 27 in a die bar 270 secured to the punch 110

guide bar, and spaced from the latter a sufficient distance to provide a space for the passage of the sheet of paper P, coming from a source of supply and passing on to 5 a take-up roll 28 mounted to turn in suitable bearings on the frame.

The take-up roll 28 has on one end a ratchet wheel 29 engaged by a feeding pawl 30 that is connected by a pitman 31 with an 10 eccentric pin 32 on one end of the main shaft, and thereby the feed motion is imparted to the paper sheet.

What I claim is:—

1. In a machine for perforating sheet 15 material, the combination of a plurality of independent reciprocable punches, a series of fingers, a shaft on which they are pivoted, means for reciprocating said shaft, and means to rock the fingers to engage and dis-

engage the fingers and respective punches, 20 each finger having a notch with punch-engaging shoulders in different planes, which alternately engage the associated punch.

2. In a machine for perforating sheet material, the combination of a plurality of 25 independent reciprocable punches having each a projection, a guide bar for the same, a die bar spaced apart from the guide bar to provide a sheet passage, a series of fingers having each spaced shoulders to engage the 30 projections on the respective punches, a shaft on which said fingers are pivoted, means to rock the fingers on the shaft and means to reciprocate said shaft.

In testimony that I claim the foregoing 35 I have hereunto set my hand.

EDGAR W. MYERS.
